TILTING SWITCH ALARM OR SIGNAL

Marius Sorensen, Astoria, N. Y.

Application May 23, 1940, Serial No. 336,772

4 Claims. (Cl. 200—52)

This invention relates to tilting switch alarm or signal.

An object of this invention is to provide a tilting switch alarm or signal which will automatically operate the alarm or signal when the switch is tilted.

A further object of this invention is to provide a wind controlled tilting switch of the character described which may be placed on a sign or in any other suitable place to actuate an alarm, signal or the like electric device.

Yet a further object of this invention is to provide a highly improved fire alarm including a tilting switch adapted to close when a part on the alarm melts by heat.

Still a further object of this invention is to provide a lamp mounted for pivotal movement and adapted to automatically become illuminated when the alarm is tilted, the lamp being rotatable about its axis to such positions that it will not illuminate even when tilted.

A still further object of this invention is to provide a strong, rugged and durable device of the character described, which shall be relatively inexpensive to manufacture, positive in action, easy to adjust, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is an elevational cross-sectional view of a lamp controlled by a tilting switch embodying the invention;

Fig. 2 is a cross-sectional view taken on line 2—2 of Fig. 1;

Fig. 3 is an elevational cross-sectional view of a switch embodying the invention controlled by wind or tilting;

Fig. 4 is a cross-sectional view taken on line 4—4 of Fig. 3;

Fig. 5 is a cross-sectional view taken on line 5—5 of Fig. 3;

Fig. 6 is a longitudinal elevational view of a tilting switch embodying the invention, and illustrating a modified construction;

Fig. 7 is a view similar to Fig. 6, and illustrating a further modified construction;

Fig. 8 is a cross-sectional view taken on line 8—8 of Fig. 6;

Fig. 9 is a cross-sectional view taken on line 9—9 of Fig. 6; and

Fig. 10 is an axial cross-sectional view of a fire alarm tilting switch embodying the invention.

Referring now in detail to the drawings, 10 designates a device embodying the invention, and comprising a member 11 having a top wall 12 and a cylindrical wall 13. The cylindrical wall 13 is formed with a pair of diametrically opposed aligned hubs 17, in which are journaled a pair of fixed aligned axles 18. Member 11 is thus tiltable about the fixed axles 18.

15 The top wall 12 of member 11 is formed with a central opening 20. Rotatably mounted within the opening 20 is a tubular member 21 made of insulating material and held against sliding movement on said top wall by a pair of split rings 22 disposed above and below the top wall and received in annular grooves 23 in said tubular member. In the bottom of the tubular member 21 is a screw shell 24 adapted to receive the base 25 of the lamp 26, screwed therein.

20 Fixed to the top of the tubular member 21 is a cap 27 of insulating material formed with a central opening 28, and an opening 29 offset from the center of said cap. Within the tubular member 21 is an inner tubular member 30 made of insulating material and formed with an opening 32 adjacent its upper end, for the purpose hereinafter appearing.

25 Within the tubular member 30 is a longitudinally extending transversely curved bar 33 formed with a bent back finger 35 at its upper end passing through the opening 32. At the lower end of the bar 33 is a spring finger 36 adapted to be engaged by the central contact 37 of the lamp base 25.

30 Mounted on the cap 27 are a pair of terminals 40 and 41 to which there are attached wires 42 and 43 connected to any source of electric power supply. The terminals 40 and 41 may be held to the cap by an insulating plate 44 screwed or otherwise attached to the cap 27. Connected to the terminal 41 is a metal bar 46 having a downwardly extending portion 47 passing through the opening 28 in the cap 27, and formed with an eye or opening 48, for the purpose hereinafter appearing.

35 Mounted on portion 47 of member 46 is a pendulum 50 having a hook 51 passing through the eye or opening 48. At the lower end of the pendulum is a metal ball 54. Attached to the other terminal 40, is a metal strip 56 passing through

the opening 29 and between the inner insulating tube 30 and the outer tube 21 and engaging at its lower end, the screw shell 24. Fixed to the cap 27 are a pair of outwardly extending handles 27a.

The operation of the device 10 will now be described:

When said device is in vertical position, the lamp will not be illuminated. When member 11 is tilted, the pendulum 50 will swing. If the tube 21 is rotated by means of the handles 27a to such a position that when member 11 is tilted, the ball 54 will strike bar 33, the lamp will be illuminated. The circuit for the lamp passes through wire 42, conductor 56, screw shell 24, the filament for the lamp, the central socket 37, the spring finger 36, bar 33, pendulum 50, conductor 28 and terminal 41.

It will now be understood that upon rotating the tube 21 by means of the handles 27a, the bar 33 may be brought to such position that when member 11 is tilted, the alarm will not be illuminated.

The lamp 26 may be replaced by any other electric alarm, device or signal if desired.

Referring now to Figs. 3, 4 and 5, there is shown a device 10a comprising a tubular insulating member 60 rotatably and non-slidably mounted in a member 61 which in turn may be mounted for rotation about a horizontal axis, in the same manner as the member 11 of Fig. 1. The tubular member 60 may be held from sliding movement in member 61 by split rings 63 received in grooves 64 disposed above and below member 61. Within tubular member 61 is an inner tubular member 65 made of insulating material.

Mounted on the upper end of the tubular member 60 is a cap 66 made of insulating material and formed with handles 67. On cap 66 is a central terminal 68 fixed thereto in any suitable manner, and three equiangularly spaced terminals 69, 70 and 71 arranged around the central terminal 68. Fixed to terminal 68 is a wire 68a, and fixed to the terminals 69, 70 and 71 are wires 69a, 70a and 71a, respectively.

Fixed to the inner tubular member 65 are three equiangularly spaced, longitudinal, transversely curved conducting strips 69b, 70b and 71b, passing through openings in the cap 66 and connected to the terminals 69, 70 and 71 respectively. The lower ends of the strips 69b, 70b and 71b may be bent back against the lower edge of tube 65.

The central terminal 68 has an eyelet 74 extending downwardly below the cap 66. Attached thereto, is the upper end of a pendulum 75. The pendulum 75 is provided with a ball 76 disposed within the tube 60. Screwed to the ball 76 is the upper end of a rod 77, to the lower end of which is attached a flat plate or vane 78.

It will now be understood that wind blowing on the plate 78 will swing the pendulum to cause the ball 76 to move toward the tube 65. If the ball 76 strikes one of the conducting strips 69b, 70b or 71b, the terminal to which said switch is connected will be electrically connected to the central terminal or common terminal 68. The wire 68a is connected in separate circuits with the wires 69a, 70a and 71a. In each of the circuits is an alarm or signal which will be selectively actuated when the circuit is closed by contact of the pendulum with the respective conducting strips. If member 61 is tilted, the pendulum will also swing, and if it contacts one of the conducting strips, the circuit for said strip will be closed.

The tube 60 may be rotated by means of the handle 67 to adjust the angular positions of the conducting strips 69b, 70b or 71b. If the ball 76 strikes the tube 65, without contacting the conducting strips, no circuit will be closed and no signal or alarm will be actuated.

If desired, the rod 77 may be unscrewed from the ball 76 so that the switch will operate merely as a tilting switch and not as a wind controlled switch.

In Figs. 6, 8 and 9 there is disclosed a tilting switch 10b, embodying the invention and illustrating a modification thereof. The same comprises a tubular member 80 made of insulating material. Screwed to the upper and lower ends of said tubular member are insulating caps 81 and 82. Attached to said caps 81 and 82 are spring clips 83 and 84, respectively. Attached to said spring clips 83 and 84 are wires 83a and 84a, respectively, which may be connected in circuit with any suitable alarm or signal device.

Integrally formed with the spring clip 83, is an eyelet 87 projecting into the tube 80. Pivoted on eyelet 87 is a pendulum 88 provided with a ball 89 at its lower end. Within the upper portion of the tube 80 is an inner tubular member 90. Between the tube 90 and the cap 82, and within the tube 80, is a coil 91 of conducting material. The spring clip 84 is attached to the lower end of the spring 91 by means of arms 93 attached to said spring clip and engaging the lowermost convolution of said coil.

When the pendulum is in vertical position, the wires 83a and 84a are not electrically connected. However, should the switch be tilted, the ball 89 will contact coil 91 to interconnect the wires 83a and 84a electrically.

In Fig. 7 there is shown a tilting switch 10c embodying the invention, and comprising an insulating tube 100 open at its lower end. Fixed to the lower end of the tube 100 is a cap 101. Mounted on said cap are a pair of spring clips 102 and 103. Connected to said spring clips are wires 102a and 103a which may be connected in circuit with any suitable electrical signal or alarm. Within the upper portion of tube 100 is an inner insulating tube 106.

Integrally formed with the spring clip 103 is an eyelet 107 projecting within the tube 106. Pivoted on eyelet 107 is a pendulum 108 provided with a ball 109 at its lower end. Screwed to the ball 109 is a rod 110 aligned with the pendulum and extending through the open lower end of the tube. At the lower end of rod 110 is a vane 111. Within the tube 100 is a metal coil 112 connected at its lower end with the spring clip 102 by means of an extension 113 at the upper end of the spring passing between the tubes 106 and 100.

It will now be understood that when the wind blows the vane 111 to tilt the pendulum, the ball 109 will contact the spring 112 to interconnect the wires 102a and 103a electrically. If desired, the rod 110 may be unscrewed so that the device 10c will operate merely as a tilting switch.

In Fig. 10 there is shown a heat responsive switch 10d embodying the invention which may serve as a fire alarm. The same comprises a horizontal insulating tube 120, one end of which is closed by a disc 121 of wax or metal of low melting point. Screwed to the other end of tube 120 is a cap 122. Fixed to the cap 122 is a spring clip 123, to which is connected a wire 123a. On said cap is a second spring clip 124, to which is connected a wire 124a.

The spring clip 123 is provided with an integral eyelet 126 projecting into the tube 120. Interconnecting the eyelet 126 with the center of the disc 121 is an axial rod 128. On rod 128 is a metal ball 129. Within the opposite ends of the tube 120 are inner insulating sleeves 129 and 130. Within the tube 120 and between the sleeves 129 and 130 is a coil 132 of conducting material. One end of the coil is connected by means of an extension 134 to the spring clip 124.

The operation of the fire alarm device 103 will now be explained.

Normally the ball 129 is spaced from the coil 132 and the wires 123a and 124 and are not electrically connected. Should the disc 121 melt however, the ball 129 will strike the coil 132 and interconnect the wires 123a and 124a electrically. Said wires may be connected to any suitable alarm or signal circuit.

The device 10d may be placed on a brakedrum of an automobile or bus and when the brake becomes too hot, a signal will be sounded to indicate to the driver that the brakes are overheated. The device 10 may be used in any other suitable manner, if desired.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A switch of the character described comprising a member having an opening, an insulating tube mounted within said opening for free rotation about the axis of said tube, a pair of terminals thereon, a pendulum connected to one of the terminals and suspended within said tube, a

conductor within the tube and adapted to be engaged by the pendulum when the switch is tilted, said conductor being connected to the other terminal, and means for mounting said member for rotation about an axis perpendicular to the axis of rotation of said tube.

2. A switch of the character described comprising an insulating tube, a pair of terminals thereon, a pendulum connected to one of the terminals and suspended within said tube, a conductor within the tube and adapted to be engaged by the pendulum when the switch is tilted, said conductor being connected to the other terminal, a member rotatably receiving said tube, means for mounting said member for rotation about an axis perpendicular to the axis of rotation of said tube, a handle on said tube, and a member attached to said pendulum and provided with a vane disposed outside of said tube.

3. A switch of the character described comprising an insulating tube, a pair of terminals thereon, a pendulum connected to one of the terminals and suspended within said tube, a conductor within the tube and adapted to be engaged by the pendulum when the switch is tilted, said conductor being connected to the other terminal, a member rotatably receiving said tube, means for mounting said member for rotation about an axis perpendicular to the axis of rotation of said tube, a handle on said tube, and wind controlled means for swinging said pendulum.

4. A tilting switch comprising a tubular member, a central terminal thereon, a pendulum suspended within said tubular member connected to said central terminal, a plurality of additional terminals mounted on said tubular member, a plurality of parallel, spaced conductors within said tubular member connected to said additional terminals, respectively, and adapted to be contacted by said pendulum when the tubular member is tilted, a member attached to said pendulum and projecting from said tubular member, and a vane on said last member.

MARIUS SORENSEN.
